PORTABLE BOAT

Will E. S. Thompson, Flagstaff, Ariz.

Application August 22, 1934, Serial No. 740,999

13 Claims. (Cl. 9—2)

This invention relates to water craft, and more particularly has reference to a portable boat.

While portable boats have been used heretofore, they have been open to certain serious disadvantages. In the first place, they are relatively expensive and difficult to manufacture. Furthermore, these boats have been of relatively fragile construction and have not been seaworthy in rough water. Even in tranquil water, most of these boats have had a tendency to readily capsize. This, of course, is particularly objectionable in a boat that is to be used for hunting or fishing, where it is frequently necessary for the occupant to move around within the boat.

15 To overcome the above disadvantages is one of the objects of my invention.

Another object of my invention is to provide a boat that is economical to manufacture and which at the same time possesses the necessary attributes for a sportman's boat.

Yet another object of my invention is to provide a boat that may be so arranged as to afford additional stability when required.

A still further object of my invention is to provide additional capacity when it is desired to increase the stability.

With the above and other important objects in view, as will more fully appear hereinafter, my invention in general comprises the several elements to be hereinafter set forth and claimed, with the understanding that these may be varied in construction, proportions and arrangement without departing from the spirit and scope of the appended claims.

35 I have shown in the accompanying drawings a specific embodiment of my improved boat, and a carrying rack therefor, it being distinctly understood, of course, that the specific structure may be departed from without exceeding the scope of the appended claims.

40 In these drawings, in which corresponding numerals refer to the same parts:

Figure 1 is a top plan view of my boat, in folded arrangement.

45 Figure 2 is a side view of my boat, with the drop box in raised position.

Figure 3 is a longitudinal section of the boat in operative position.

50 Figure 4 is a top plan view of the boat arranged to give additional stability, and with the drop box in lowered position.

Figure 5 is an elevational view of the drop box in lowered position.

55 Figure 6 is a detail view of the means for locking the foldable members in operative position.

Figure 7 is a sectional view along the line 7—7 of Figure 6.

Figure 8 is a detail view of a locking means for holding the foldable members in extended position.

Figure 9 is a sectional view along the line 9—9 of Figure 8.

Figure 10 is a rear elevation of the carrying means for the boat.

Figure 11 is a side elevation of the rack assembled upon an automobile.

Figure 12 is a sectional view along the line 12—12 of Figure 10, looking in the direction of the arrows.

Referring in more detail to Figure 1, it will be observed that my boat is made up of a main body section 1 and two foldable sections 2 and 3. The sections 2 and 3 form in effect air tight compartments. These sections may be composed of wood, light weight metal, or any suitable composition that is sufficiently waterproof. In this connection, and in all other connections, I do not desire to be limited to any specific type of material for the construction of my boat, or the rack therefor.

It will be observed that the body section 1 is provided with a suitable cockpit 4 surrounded by the usual coaming 5. A seat 6 is provided at one end of the cockpit, and the coaming extends therearound. As best shown in Figure 3, the coaming may also extend beyond the cockpit to form a raised deck 7 at the end opposite to the seat. A footrest 8 may be provided in the cockpit to afford a suitable purchase for the occupant when rowing. When in lowered position, the footrest 8 may rest upon spaced bars 9 and 11, being hinged to bar 11 so that it may be swung to the position indicated by the dotted lines in Figure 3 during an actual rowing operation. At other times, it may be lowered to rest upon the bar 9, at which time a vertical member 10, extending from the deck to the base of the cockpit, may serve as a headrest when the boat is carried.

The foldable section 2 is pivoted to the body section 1 by means of hinges 12 and the foldable section 3 is pivoted to the body section by hinges 13. It will therefore be noted that the sections 2 and 3 can be folded back upon the sides of the body member as shown in Figure 1, and in this position the boat may be readily carried by an individual. To facilitate the opening and shutting of the sections 2 and 3 while the boat is on the water, I provide handles 14 upon each of the sections 2 and 3 which may be readily gripped by the occupant. I also provide suitable

5

20

25

30

35

40

45

50

55

locking means 15 to lock the sections 2 and 3 in the folded position.

The sections 2 and 3 may be extended to the position indicated by the dotted lines in Figure 1. From an inspection of Figures 1 and 3 it will be observed that the seat 6 extends beyond the limits of the body section 1, and the foldable sections 2 and 3 swing therebeneath.

As stated above, the main coaming extends around the seat 6, but when the boat is in assembled position I prefer to have an auxiliary coaming, designated generally 16, which extends further out over the sections 2 and 3. Specifically, the auxiliary coaming 16 is composed of side members 17 and 17a which are hinged as at 18 and 18a to the end of coaming 5. By virtue of suitable locking means 19 and 19a, respectively, the members 17 and 17a may be locked in a position parallel to the sides of the coaming 5. At the end of the members 17 and 17a, opposite the locks 19 and 19a, I provide an end member 21 to form a transverse section of the auxiliary coaming. The end member 21 is secured to the side members 17 and 17a by hinges 22 and 22a. The bolts of these two members are removable, for a purpose to be described hereinafter, or the hinge 22a may be of a permanent type, while the hinge 22 might be substituted for by an optional locking member.

The auxiliary coaming serves to make the boat more rigid and also furnishes a rest on which to stand the boat in raising and lowering it from the ground.

During movement on the water, it is of course desirable to insure that the members 2 and 3 will be locked in the position shown by the dotted lines of Figure 1. While various locking means may be employed, I have shown one particularly advantageous type in Figures 6 and 7. This locking means is indicated generally by the numeral 23 in Figure 1, and more specifically comprises a buckle tongue 24 which is pivoted to a frame 25 secured to the inner side of end member 21. The tongue 24, as clearly shown in Figure 7, is pivoted at its lower end by the bolt 26, and the actual point of pivot is eccentric.

Intermediate the pivot 26 and the free end of the tongue 24, a buckle 27 is carried by the tongue. Each of the sections 2 and 3, at the proper points along their straight edges, is provided with a hook 28 which is countersunk, as shown in Figure 6, to permit the two members to be entirely closed, so that their straight sides are flush with each other. The buckle 27 is adapted to engage at the same time both of the hooks 28, and upon raising the tongue 24 to the position shown in Figures 6 and 7, the members 2 and 3 are securely locked in closed relationship. It is of course obvious that the tongue should be mounted on the end member 21 at a point equi-distant from its ends, and that the hooks 28 are located at the points so that when the members 2 and 3 are closed, the hooks may be engaged by the buckle.

Under normal conditions, my boat possesses sufficient stability for all usual purposes. However, in the event of rough weather, or operations in which increased stability is desired, I have provided means for securing such stability by partially opening the sections 2 and 3, as clearly shown in Figure 4. This presents a desired advantage over prior constructions, as will be appreciated. To maintain the sections 2 and 3 in such a position, I have provided locking means for each of the sections which I designate generally as 29. These locking means comprise frames 31 and buckle tongues 32 pivoted eccentrically to the

frame 31 by the bolt 33. The frames 31 and tongue 32 correspond generally to frames 25 and 24 of Figures 6 and 7.

However, the buckle in this case is altered, and comprises a rod 34 which is bent as at 36, and is pivoted to the tongue 32 intermediate the length of the latter. A further bend 37 securely holds the rod 34 in the tongue. The lower end of the tongue forms an eye 38 which carries a freely swinging hook 39 provided with an eye 41 which engages the eye 38. The free end of the hook 39 is bent, as at 42, and is adapted to be inserted into a recess 43 in the straight sides of the sections 2 and 3. A suitable countersunk and reinforcing strip 44, preferably of metal, may be secured to the sections adjacent the recess 43. This affords a secure lock for the hook 39.

It will of course be appreciated that the frames 31 and tongue 32 must be located outwardly from the center of the end member 21 and that the recesses 43 and plate 44 must be so positioned along the length of the sections 2 and 3 as to afford engagement with the hook 39. The exact location of these several elements will of course depend upon the amount of spread of the sections 2 and 3 that is desired by the operator of the boat. It is obvious that a plurality of locking means 44 may be provided in order to secure different amounts of spread.

Referring to Figures 2 and 3, I have provided an auxiliary seat, designated generally by the numeral 45, and which I term a drop box. This is adapted for use when the sections 2 and 3 are in a spread position, as shown in Figure 4, as it will be appreciated that the occupant can then occupy the drop box in lieu of the seat 6 or some other portion of the main body member 1. The drop box affords a lower position in the water, thus better concealing the occupant and also furnishing protection from the wind. It also affords a more stable position when standing to shoot or fish.

This drop box comprises in general a waterproof box which may be lowered into the water intermediate the two sections 2 and 3.

Specifically, it is made up of side members 46 and 47 and end members 48 and 49. The bottom is composed of a horizontal portion 51 and a seat indicated by the dotted line 52 in Figure 2. An upright member 52' joins the horizontal portion 51 and seat 52. The end member 49 is preferably secured to the end member 21 of the coaming by hinges 53, although it is of course obvious that positive locking means may be employed. I prefer hinges, because they permit the drop box to be swung up or let down, as desired. A rope 54 may be employed to retain the drop box in raised position.

In order to afford additional support for the drop box when in lowered position, I have provided wings 55 and 56 which are hinged, as at 57 and 58, to the free ends of side members 46 and 47, respectively. The wings 55 and 56 may be tapered, as shown clearly in Figure 2, and the free ends of the wings are provided with notches 59 which are adapted to receive the foldable members 2 and 3. As shown in Figures 4 and 5, the wings may be swung outwardly so that the notches 59 engage the two folding sections. Those parts of the wings surrounding the notches 59 engage the upper, lower and side portions of the folding sections, as best shown in Figure 5. The drop box is thereby supported by the folding sections as well as by the end member 21.

Obviously, when the boat is folded the auxiliary

coaming would normally constitute an unnecessary impediment. However, I have provided means for reducing the extensible character of this coaming by folding the same upon the main 5 coaming 5, as best shown by the dotted lines in Figure 1. To accomplish this, I remove the bolt in hinge 22 (or if a locking means is employed in lieu thereof I unlatch it), unlatch the lock 19 and then fold the member 17 to the position shown 10 by the dotted lines 17 of Figure 1.

It will be noted that the hinge 18a is somewhat extended from the coaming 5 so that the member 17a can be folded over the folded member 17, upon unlatching of the lock 19a. When the member 15 17a is folded to the position of the dotted lines 17a, the member 21 is swung on the hinge 22a so that it forms a continuation of the side member 17a, as indicated by the dotted lines 21 of Figure 1. All this considerably reduces the 20 area occupied by the boat when in folded position.

Oarlocks 61 may be provided, and I prefer that they have channels 62 extending through them for the reception of the handles of oars. I also 25 provide additional oar braces 63 which, in conjunction with the channels 62, serve to securely hold the oars during a portage of the boat.

In Figures 10 through 12 I have shown a simple, but efficient, rack for carrying the boat on an 30 automobile or other conveyance. This rack is made up of the base member 64 and crossbars 65 and 66, all of which are suitably secured to angle irons 67 and 68 forming the sides of the rack.

35 This rack may be quickly attached to, or removed from, an automobile by means of the fastening device I employ. As best shown in Figure 12, the base member 64 is in effect an inverted channel iron provided with an upwardly extending lip 69. The channel of the channel iron is of sufficient width so that the boat, when applied to the rack, rests securely thereon.

Extending downwardly from the base member 40 64 are two uprights 71 which are adapted to rest upon the top bar of the bumper 72 on the rear of the automobile. At the inner base of each upright 71, I provide a hinge 73, to which is secured an iron strap 74. Although I prefer the use of a hinge 73, it will be appreciated that under 45 certain circumstances the hinge may be dispensed with and the strap 74 may be rigidly secured to the uprights 71.

The lower end of strap 74 is provided with a hinge 75 which carries a lip 76. The lip 76 50 is slotted from its end as at 77 and is adapted to receive a bolt 78 which extends through the strap 74 and under the lower bar of the bumper 72. A wing nut 79 is provided to securely clamp the lip 76 against the lower bar of the bumper. The slot 77 permits the lip 76 to be swung on its 55 pivot without entirely removing the wing nut from the bolt. It will be appreciated that the rack may be quickly assembled upon the bumper or removed therefrom.

60 The upper portion of the rack rests against the rear of the automobile and is secured thereto by means of straps 81 and 82 which are provided with buckles 83 and tongues 84. The strap is buckled around the window post 85 of the automobile when the windows are slightly lowered. Straps 86 and 87 extend across the rack and hold the boat securely upon the rack. As pointed out above, the flat section of the body portion 65 and the foldable portions 2 and 3 rest securely upon the channel iron 64. The lip 69 and the

straps 86 and 87 maintain the boat in this position on the rack.

The folded boat is assembled upon the rack as indicated by the dotted lines in Figure 10. That portion of the seat 6 extending beyond the body member 1, as well as the folded auxiliary coaming 16, project beyond channel iron 64, but it will be noted that they do not extend below the bumper. They are thereby protected from damage in the event of the roughest kind of roads, and it will be noted that most of the boat is within the confines of the rack. As best shown in Figure 10, when the boat is assembled upon the rack, the drop box 45 may be carried inside section 1 of the boat.

15 The utility and operation of my boat is believed to be readily apparent from the foregoing. It will be appreciated that it can be readily folded to take up a minimum of space and means are provided for an easy carrying of the boat 20 when in this condition. It will also be appreciated that the boat may be quickly assembled to a completed water craft, and may also be arranged to insure additional stability. The drop box 45 is a decided advantage when the boat is 25 at anchor and cooperates with the extended sections 2 and 3 to afford additional stability and protection for the occupant.

The rack which I have provided is an efficient 30 and satisfactory means of carrying the boat on an automobile or other vehicle, and, together with the boat, may be quickly assembled upon a vehicle.

It is, of course, obvious that various modifications may be made in the embodiment depicted 35 in the drawings and described in the specification. For example, the boat need not be pointed at both, or either, end, and various details may be omitted or altered, such as the drop box, auxiliary coaming, and numerous other features. However, with respect to all additions, omissions and modifications, I wish it to be distinctly understood that I am to be limited solely by the scope 40 of the prior art and by the appended claims.

I claim:

1. A boat comprising a body composed of a rigid non-collapsible portion and two segments, said segments being foldable upon the non-collapsible portion, a coaming on the non-collapsible portion and an auxiliary coaming extending over the foldable segments when the latter are extended, and means on the auxiliary coaming for locking the foldable segments in extended or semi-extended position.

2. A boat as specified in claim 1, in which the auxiliary coaming may be collapsed.

3. A boat such as specified in claim 1, and provided with a compartment adapted to be lowered from the auxiliary coaming into the water between the hinged segments when in a spread position.

4. A boat such as specified in claim 1, in which the compartment is hinged to the auxiliary coaming.

5. A boat having a body composed of an integral portion and two segmental portions hinged laterally to form a relatively non-capsizable boat, an auxiliary water-tight compartment adapted to be lowered into position between said two sections, and means for securing said auxiliary compartment and said segmental portions in fixed relation to each other.

6. A boat comprising a body composed of a rigid non-collapsible portion and two segments,

5

- said segments being foldable upon the non-collapsible portion, a coaming on the non-collapsible portion and an auxiliary coaming extending over the foldable segments when the latter are extended, means on the auxiliary coaming for locking the foldable segments in spread-apart position, an auxiliary compartment adapted to be lowered between said segments and provided with hinged wings adapted to engage said segments and to hold said segments and said compartment in fixed relation to each other.
7. A boat comprising a body of a rigid non-collapsible stern portion and two float members, said float members being hinged to opposite sides of the front portion of the rigid non-collapsible portion and adapted to be swung together in the same plane as the rigid noncollapsible portion of the boat to form a bow portion of said boat.
8. A boat comprising a body composed of rigid non-collapsible stern portion and two float members, said float members being hinged to opposite sides of the front portion of the rigid noncollapsible portion and adapted to be swung together in the same plane as the rigid portion of the boat to form a bow portion of said boat, and means for locking the float members in said bow position.
9. A boat comprising a body composed of a rigid non-collapsible stern portion and two float members, said float members being hinged to opposite sides of the stern portion of the rigid noncollapsible portion and adapted to be swung together to form a bow portion of the boat or to be folded laterally upon the rigid noncollapsible portion to form a compact unit easily transported.
10. A boat comprising a body having an integral stern portion and two float members, said float members being hinged to opposite sides of

the front end of the integral portion and foldable upon opposite sides of the said integral portion and said float members being adapted to be swung together laterally to form the bow portion of said boat.

11. A boat comprising a body composed of an integral stern portion and two float members, said float members being hinged to opposite sides of the front end of the integral portion and foldable upon opposite sides of the said integral portion and adapted to be swung together laterally to form a bow portion of said boat, and means for locking the float members in said bow position.

12. A boat comprising a body having an integral stern portion and two float members, said float members being hinged to opposite sides of the front end of the integral portion and foldable upon opposite sides of the said integral portion and adapted to be swung apart laterally to form a relatively noncollapsible boat, and means for locking the float members in spread apart position.

13. A boat comprising a body having an integral stern portion and two float members, said float members being hinged to opposite sides of the front end of the integral portion and foldable upon opposite sides of the said integral portion, the float members being adapted to be swung apart laterally to form a relatively non-capsizable boat, and an auxiliary compartment adapted to be lowered between the float members and provided with hinged wings adapted to engage the float members and to hold said float members and the compartment in fixed relation to each other.

WILL E. S. THOMPSON.
